FILING BOOK FOR DATA CARDS

Albert L. Christiansen, Joliet, and Lucius J. Boynton, Lockport, Ill.

Application September 3, 1937, Serial No. 162,360.

4 Claims. (Cl. 129—34)

This invention relates to a filing facility for cards upon which information is recorded, and the object is to provide unit storage facilities in the form of books which may be easily handled for reference and in each of which a large number of cards may be replaceably introduced, left readily accessible and stored in a minimum of space without obscuring distinguishing marks by which they are, respectively, identified.

The invention proceeds upon the principle of constructing the unit storage facility in the form of a book comprising cover boards of rigid self-sustaining structure, a flat plate-like back to the margins of which the covers are, respectively, hinged, and a plurality of leaves provided on one or both sides with retaining cleats through means of which a relatively large number of cards may be racked in overlapping mutually sustaining position, with a portion of each card exposed sufficiently to afford inspection of an identifying number, character or other marking without disturbing the cards, and with the resultant stack of cards readily separable at any card for exposure of more of its surface when it becomes necessary to use information recorded thereon or record data in addition to that which it already bears; to which end, the manner of confining the cards upon the surface of the leaf is such as to present the surface of a card, when it is exposed by dividing the stack, in condition to be written upon. A plurality of these leaves are mounted between the covers of the book by pivotally anchoring each leaf to the back through means of a rigid marginal strip that is hinged to the body of the leaf; the pivotal anchorage being effected through means of slots in the strips that receive staples positioned transversely of and upstanding rigidly from the back and retained in the slots by replaceable rods socketed in the hinging strips so that when a number of leaves are assembled in the book, their special flexible anchorage will permit them to lie flat, one upon another, in the opening of the book, a function which is promoted by arching the rigid staples; and when the book is closed and stood upon end, each leaf will, by reason of the nature of its anchorage, its inherent structure and its reinforcement against flexure, be rendered self sustaining against sagging under gravity.

The invention resides in certain features of construction and cooperation of the assembled parts hereinafter pointed out in the claims.

In the accompanying drawings—

Figure 1 is a perspective view of a record card

storage book embodying the several features of the present invention.

Figure 2 is a sectional view of the back of the book and portions of covers hinged thereto, and shows in plan a rigid upstanding anchoring 5 staple mounted upon the back.

Figure 3 is a plan view of an index card specially constructed for mounting upon the leaves forming part of the present invention.

Figure 4 is a section taken from side to side of 10 one of the book leaves and showing a card and the two cleats through means of which it is mounted upon the leaf.

Figure 5 is a detail view, on an enlarged scale, 15 of a portion of one of the leaves, with one of its cleats and the means through which the leaf may be pivotally anchored to the back.

Figure 6 is a section on the line 6x—6x of 20 Figure 5 showing the manner of stacking cards on opposite sides of the leaf, the cards being somewhat spread apart to permit them to be distinguished individually and the better to show their relation in the stack.

Figure 7 is a bottom end view of a book, minus 25 one of its covers and having a plurality of leaves assembled therewith and grouped thereon in a manner permitted by their special hinge structures so that the several leaves will lie flat one upon another when the book is opened.

1 represents the back, 2 the covers and 3 30 leaves of the card filing book forming the subject matter of the invention. In Figure 1, one of the leaves has its upper portion broken away to disclose the cover structure behind it. Covers 2 are united to the back 1 through the medium of hinges 4 comprising, in addition to their pintles 4a, a back plate 5 and two cover-attaching plates 6. Covers 2 are of board-like structure, made of any suitable rigid material and are reinforced against flexure by the hinge plate 6. The back 1 35 comprises a flat plate 1a reinforced by the plate 5 which likewise constitutes a rigid structure so that the back and covers are adapted to stand on end and sustain the card-storing leaves between them.

The leaves 3 are assembled in the book through 40 means of anchor strips 7 constituting the inner marginal portions of the leaves hinged to the leaves at 8 and pivotally anchored to staples 9 through means of slots 10. In the anchor strips 7 are replaceable rods 11, of which there is one 45 socketed in the innermost margin of each anchor strip and which rod engages the strip with the staples 9 where the rod crosses the aforesaid slots. Staples 9 extend transversely of the back 50

55

1, being conveniently positioned by having their ends 9a headed into the hinge plate 5; and they are oblately arched so that they extend outwardly from as well as transversely to the back of the 5 book. Their attachment affords sufficient rigidity, under the gravity load of the leaves and the cards which they bear, to prevent sagging of the leaves when the closed book is stood on end. The upstanding character of these staples, their 10 extension outwardly and transversely of the back and the special hinging effect afforded by the anchor plates 7, pintles 8 and pivotal anchorages 10 and 11 combine to avoid interference between the hinges 8 of the several leaves and permit the 15 leaves, notwithstanding card-stacking cleats 12 provided thereon, to lie in flat superposed position with any selected leaf presented for convenient inspection when the book is opened thereat.

To mount the cards upon the leaves of a filing 20 book constructed as above described, each leaf is provided upon at least one and preferably both of its faces with a pair of undercut stacking cleats 12, each cleat being spaced from the leaf by a strip 12a and being united to the leaf through 25 means of rivets 13 along one edge of the cleat, with a spacing shim 14 that serves as a card-arresting stop at the lower end of each cleat and preferably a shim 15 at the upper end of each cleat as well, in order to prevent upward escape 30 of the cards when a column of cards is lifted. Each cleat is thus provided with an under space throughout its length but closed top and bottom, into which tangs 16 on card 17 may be introduced as a means of holding the cards in place. Tangs 35 16 are near the ends of the cards though leaving uninterrupted card margins 17a beyond them and the cleats are spaced appropriately to underlie these card-ends 17a while receiving the tangs and leave intermediate portions of the card spaced 40 from the leaf upon which the cards are mounted and subject to slight depression of any card while grasping the upper exposed margin of a desired card at an intermediate balancing point and drawing it, together with those stacked above it, 45 upwardly to expose the full surface of the selected card to inspection or amendment of its record.

Inasmuch as the tangs of each card, in entering the under spaces of the cleats, are deflected from the plane of the card and cross the lower 50 edge of the next higher card, these tangs serve to limit the telescoping of all cards above the bottommost card (which is arrested through its tangs by the bottom shims 14) and the tangs of each card thus become the means of causing any 55 card selected to be inspected and all those which lie above it to move upward in column. The spacing of the tangs a selected distance above the bottom edge of the card which carries them will determine the projection above each card 60 of the upper margin of the next higher card upon which indexing or other marks of card identification are placed and kept permanently in view. The cards are stacked by introducing them in any desired order upon the cleats and pressing 65 each card downwardly until its lower edge is arrested by the tangs of the next lower card. The introduction of a card in an intermediate position is practicable at all times by merely raising the column at and above any card sufficiently 70 to admit beneath it the card that is to be introduced. Similarly, any card can be removed when desired and the remaining cards restored to compactly telescoped stacking.

The card filing device of book type herein 75 described affords special advantages in the filing

of cards upon which are kept records of arrival and departure of railway cars as well as disposal of said cars between arrival and departure, the nature of their cargo and other data that may be required to be recorded pursuant to an established system; and particularly such a device when used in a system that involves introduction of a new card for each railway car that arrives and the disposal of such card, such as permanently filing it away after the departure of the car 10 in order that it may not encumber the working filing system. 5

Referring more in detail to the preferred embodiment of the invention and as shown more clearly in Figure 2, the back 1 may be built up of 15 the back plate 1a of fiber board or any suitable rigid material, the butt-plates 6 of hinges 4, and the face plate 5 already referred to and into which the heads 9a of staples 9 may be countersunk and riveted. Similarly, the leaves 3 may 20 have their butt-plates 8a of hinges 8 formed independently of the cleats 12, and the latter may be laminated by the use of strips 12a through which pass the rivets 13 in providing the under spacing for the tangs 16 and shims 14-15 which 25 close the ends of the under spaces.

An important identifying characteristic of the preferred embodiment of the invention resides in the employment of the anchoring strips 7 hinged to both the leaves 3 and the staple 9 and offsetting the inner margins of the leaves to planes which permit them to assume parallel positions, one above another, when the book is open, as shown in Figure 7, and particularly freedom of the strips 7 to vary the elevation of each leaf 30 by assuming an appropriate angular position or by the amplitude of movement permitted by its slots 10 relatively to staples 9. If approximately all the leaves were turned to one side, the offsetting strips 7, which at the time engaged a relatively low portion of an arched staple 9, would be permitted by the lost motion afforded by the depth of its slots 10 to raise the leaf to a level above the very considerable number of leaves which must be accommodated beneath it; 45 and, conversely, the lost motion spaces 10 will permit foreshortening of the offset effected by the strip 7 of those intermediate leaves, the anchorages of which occupy intermediate positions upon the arched staples. 50

A further important function served by the particular manner of mounting the leaves in the book arises from the ready releasability of the leaf, preferably at its anchorage between the strip 7 and the staple 9, and the removal of the 55 leaf from the book when convenience requires or the rearrangement of the order of the leaves in the book, and to permit which the anchoring strips are preferably made all of one width.

It is noted that in the superposing of one leaf 60 upon another in the open position of the book, hinge 8, which joins an anchoring strip to the body of a leaf, will assist in spacing a superposed leaf sufficiently to avoid rubbing or displacement of the cards on the leaves. 65

What is claimed is:

1. In a card filing device of the book type, hingedly connected back and cover elements adapted to open into a single flat plane, and leaf elements; said leaf elements comprising rigid 70 board-like bodies having card embracing means near their inner and outer longitudinal margins and having at their inner margins inherently rigid anchoring strips hingedly connected to the bodies of the leaf elements and anchored to the 75

- back of the book by curved securing means and adapted to offset each of the hinges which connect them with the leaf bodies to a plane that permits each of the bodies, when the book is entirely open, to lie flat with respect to an accumulation of leaves beneath it and thereby offset inwardly toward the back, each leaf relatively to the one beneath it, and thereby avoid interference of the card-engaging means on any leaf with the card-engaging means on the leaf beneath it.
2. A card filing device as described in claim 1, in which the anchorage between the strips and the back is constructed to permit swinging movement at the anchorage, together with lost motion between the strips and the anchorage in the direction of the radius of such swinging movement together with bodily movement of the leaves and their anchoring strips in a direction substantially parallel to the plane of the fully open book.
3. A card filing device as described in claim 1, in which the anchorage of the strips to the back comprises a slot in each of the strips and a staple on the back engaging in said slots; the staple being confined in the slots by a rod socketed in the margin of each of the strips and crossing the slot behind the staple; and the slots being

elongated in the direction of the radius of swinging movement of the leaves and affording variation in the radial offset of the body of the leaves through means of said strips and the staple being of low arcuate or oblate form and affording an amplitude of movement in a direction perpendicular to the back which is relatively small compared with the movement afforded by the sliding of the anchoring strips on the staple.

4. In a card filing device of the book type, the combination of hingedly connected back and cover elements adapted to open into a single flat plane, leaf elements comprising rigid board-like bodies having means thereon for securing cards, rigid anchoring strips hingedly connected to said leaf elements adjacent their inner margins, curved anchoring means connected to the back of said book and to said anchoring strips and adapted to offset each of the hinges which connect said strips to said leaf bodies to a plane that permits each of the bodies, when the book is entirely open, to lie flat with respect to an accumulation of leaves beneath it.
